UNITED STATES PATENT OFFICE.

ALVAH RICE, OF ROCHESTER, NEW YORK, ASSIGNOR OF ONE-HALF TO
STEPHEN WHEELER, OF SAME PLACE.

CAR-COUPING.

SPECIFICATION forming part of Letters Patent No. 271,272, dated January 30, 1883.

Application filed December 18, 1882. (No model.)

To all whom it may concern:

Be it known that I, ALVAH RICE, of Rochester, in the county of Monroe and State of New York, have invented a new and useful 5 Improvement in Car-Couplers, which improvement is fully set forth in the following specification and accompanying drawings.

The object of my invention is to produce a simple device for coupling railroad-cars; and 10 it consists in inserting a piece or body of simple form within the draw-bar in common use, capable of being moved longitudinally therein and adjusted to hold either the link or pin in place while in the act of coupling cars together, 15 the same being fully described hereinafter, and more particularly pointed out in the claims.

Referring to the drawings, Figure 1 is a side elevation of my improved car-coupler, with parts sectioned and broken away; Fig. 2, a 20 similar view, showing some of the parts in different positions; Fig. 3, a plan of the same with parts sectioned and broken away, viewed as indicated by the arrow *y* in Fig. 1; and Fig. 4, a front end elevation of the same, viewed as 25 indicated by the arrow *z* in Fig. 1.

Referring to the parts, A is the upper, and B the lower, horizontal bar or member of the draw-bar; C, the bumper-ring of the same; D, the coupling-link, and F the pin thereof, all of 30 common construction.

G is the block of hard wood, commonly secured between the wrought-iron members A and B to add strength and stiffness to the body of the draw-bar. This block I divide vertically 35 and longitudinally into two equal pieces, *f* and *f'*, leaving a space, *b*, about one inch wide between them, said space *b* being surrounded by the four side walls or sides, A B and *ff'*, of the draw-bar.

I is a sliding bar or body of suitable length, 40 fitted to slide freely longitudinally within the space *b* between the side walls, being narrower vertically than said space, and made to rest at its lower edge upon the lower member, B, of the draw-bar. This sliding bar is T-shaped in plan, as shown in Fig. 3, having vertical projecting strips *a a* secured at the sides thereof and flush with the front end of the said sliding bar, which strips serve the purpose of widening 45 the end face or end, *g*, of the sliding bar I,

so as to receive the end of an approaching link as the latter enters the bumper-ring C and cause the said sliding bar to be moved back by the link in the act of coupling. These strips *a a* also form finger-rests for the operator, by 55 means of which to move said sliding bar longitudinally without the draw-bar, as above stated, in the operation of coupling cars together. The rear faces or shoulders, *c c*, of the strips meet the ends of the blocks *f f'* when the sliding bar 60 is moved back from the bumper-ring, as shown in dotted lines in Fig. 3, and form stops for said sliding bar in its backward movement, and on account of the concave form of the strips spaces *e e* are left between the rests *a a* and 65 ends of the respective blocks *f f'* for the purpose of inserting the fingers to draw the sliding bar forward, as stated. When the sliding bar is drawn forward the upper part of the face *g* comes in contact with the inner surface 70 of the bumper-ring at *h*, which forms a stop for the sliding bar to prevent it being at any time drawn out of the draw-bar.

When it is wished to couple the draw-bar shown onto another car the sliding bar I is drawn 75 forward by hand, as above described, to the position shown in full lines in Fig. 1, with the pin raised and resting upon the upper surface of said sliding bar. The link D of the approaching car impinging against the face *g* of 80 the sliding bar pushes the latter back to the position shown in dotted lines, when the pin drops through the link and the coupling is completed. If it is wished to hold the link in position to enter the opposing bumper of an approaching car for the purpose of coupling, the sliding block I is drawn forward and raised at 85 its front end, so as to rest upon the end of the link, as shown in Fig. 2, the end of the link occupying the notch *d* in the lower front corner of the sliding bar. The pressure exerted against the under side of the sliding bar by the link when in the position shown, on account of the leverage of the latter from overbalancing 90 outside of the bumper-ring, holds the front end of the sliding bar up against the under surface of the member A of the draw-bar, which pressure of the link upon the sliding bar is sufficient 95 to hold the former in place for the purpose of effecting the coupling with the other car. The 100

upper side, *i*, of the notch is made inclining, as shown, for the purpose of accommodating links of different sizes.

I claim as my invention—

- 5 1. In a car-coupler, in combination with the parallel bars or members A and B and blocks *f* and *f'* of the draw-bar, and the bumper-ring C, link D, and pin F, the sliding bar I, fitted to slide longitudinally within the space *b* in-
10 closed between said members A and B, and blocks *f* and *f'*, said sliding bar I being provided with finger-rests *a a* and shoulders *c c*, sub-

stantially as shown, and for the purpose set forth.

2. The combination of the sides or walls A B 15 and *f f'* of the draw-bar, and the bumper-ring C, link D, and pin F, with the sliding bar I, pro-
vided with the finger-rests *a a*, shoulders *c c*, and the notch *d*, in which to hold the end of the link, substantially as set forth and shown. 20

ALVAH RICE.
